UNITED STATES PATENT OFFICE.

WILLIAM T. CARNES, OF KANSAS CITY, MISSOURI, ASSIGNOR TO CARNES ARTIFICIAL LIMB COMPANY, OF KANSAS CITY, MISSOURI.

PHONOGRAPH TONE ARM AND RESONATOR.

Application filed December 19, 1923. Serial No. 681,512.

My invention relates to phonographs and particularly to the tone arm and amplifier thereof.

The object of this invention is to provide a tone arm which is swivelled on the upper end of the amplifier and will have no joints and restricted portions between said swivel and the sound box. Also to form said tone arm on the lines of a parabola, gradually increasing in diameter from the free end thereof to said swivel. Also to form the small end of the amplifier on the lines of a parabola, thus eliminating the right angle elbow curves in said tone arm and amplifier. Also to provide a hinge-swivel joint between the tone arm and amplifier.

These and other features of my invention will appear hereinafter and are illustrated in the accompanying drawings, in which:

20 Figure 1 is a side elevation of my improved tone arm and amplifier.

Figure 2 is a vertical section of my improved hinge-swivel joint on the line 2—2 in Fig. 1.

25 Figure 3 is a transverse section of the same on the line 3—3 in Fig. 1.

Figure 4 is a side elevation of the swivel ring of my invention.

30 Figure 5 is a plan view of the same.

Figure 6 is a rear view of the lower end of the bar G.

In these drawings, A indicates my improved tone arm, A' indicates a sound-box, and B indicates my improved amplifier. B' 35 is the curved neck of the amplifier B which joins the tone arm A.

I have eliminated the usual sharp curve of a right angle elbow, and in lieu thereof my improved tone arm A is formed with the 40 gradual curve of a parabola from the free end a to the swivel end a', the diameter thereof gradually increasing from the end a to the end a' of the tone arm, thus eliminating, as far as possible, interior pockets wherein there 45 is little or no longitudinal progress of tone waves within the tone arm A.

Within the free end a of the tone arm A is inserted the neck a² of the sound-box A', which is secured therein by means of a set 50 screw a². This sound-box, shown in the accompanying drawings, is the subject of a separate application and forms no part of this invention.

The resonator B is provided with an up- 55 turned neck B', which like the tone arm A

is formed with parabolic curves, thus reducing the sharp curves of a right-angle elbow, so that the natural expansion of sound waves is not interfered with.

On the upper end of the neck B', I place a 60 spider-ring, C, which is secured firmly in place by means of bolts C' which pass through ears b, on opposite sides of the neck B' and screw into ears c on opposite sides of the spider-ring C. 65

From the hub of the spider-ring, an upright post D projects upwardly, and upon this post D another spider-ring E is journaled, the hub E' of the ring E is tubular and extends above the upper end of the 70 post D.

Upon the upper end of the post D, I place a ball, e, and within the upper end of the hub tube E' is placed an adjusting screw F which carries the ring E free from the 75 spider-ring C. In the upper edge of the ring E are found slots e' e' at opposite sides of said ring which receive studs f f riveted in diametrically opposite sides of the wall of the tone arm, which permits a vertical swing 80 of the tone arm with relation to the ring E, while the ring E will freely turn on the post D.

Riveted or otherwise secured to the tone arm A is a bar G which extends downwardly 85 to a point opposite the rear of the amplifier B. The lower end of the bar G is provided with a slit g, and a clip G' is pressed over the lower end of said bar G being retained thereon by the friction of said clip on the bar, 90 enhanced by the elasticity of the split end of said bar.

Secured to the frame H of the machine is a bracket H' which projects forwardly to the line of the axis of the swivel post D, 95 and secured to the clip G' on the bar G is a cable H² which is also secured in the bracket H' and which serves to suspend the tone arm A in the proper vertical elevation. The elevation of the tone arm A can be 100 properly adjusted by means of the screw F in the upper end of the hub tube E'.

Having thus fully described the construction of my invention, the operation thereof will be so obvious that further description 105 thereof will be unnecessary, therefore what I claim as new and desire to secure by Letters Patent is:

1. In an apparatus of the class described, an amplifier, a spider-ring secured upon 110

the receiving end thereof, an upright post supported upon said ring, a swivel ring journaled on said post, means to give vertical adjustment to said ring with relation to said post, said ring having vertical slots in its upper edge at diametrically opposite points along the upper edge of its periphery, a tone arm adapted to receive said ring, and trunnion studs secured in the wall of said arm and adapted to enter said slots.

2. In an apparatus of the class described, an amplifier, a spider ring secured on the receiving end thereof, an upright swivel post supported on said ring, a swivel ring having a tubular hub and having vertical notches in the upper edge thereof and having said tubular hub journaled on said upright post, an adjusting screw in the upper end of said tubular hub adapted to support said swivel ring free from said spider ring, a tone arm adapted to receive said swivel ring, trunnion posts secured in the wall of said tone arm and entering said vertical slots, and means to limit the downward swing of said tone arm on said trunnion posts.

3. In an apparatus of the class described, an amplifier, a tubular swivel on the upper end thereof, and a tapered, parabolic, tone arm having the base thereof trunnioned on said swivel.

4. In an apparatus of the class described, an amplifier, a tubular swivel on the upper

end thereof, a curved tone arm trunnioned on said swivel, and means to support the 35 free end of said tone arm.

5. In an apparatus of the class described, a tubular swivel ring having oppositely disposed trunnion receiving slots in the upper edge thereof, a curved tone arm, trunnion 40 posts on said tone arm adapted to rest in said slots, a downwardly extending arm secured to the rear of the said tone arm, a case to enclose the said apparatus, and means to anchor the lower end of said arm to said 45 case of said tone arm.

6. In an apparatus of the class described, an amplifier, a spider ring secured on the receiving end thereof, a swivel post extending upwardly from said ring, a swivel ring having notches extending downwardly in diametrically opposite points of the upper edge thereof, a tubular hub connected to said ring and journaled on said post, a screw in the upper end of said tubular hub adapted to support said swivel ring out of contact with said spider ring, a tone arm adapted to receive said swivel ring, trunnion studs on the inner surface of said tone arm adapted to be lowered into said notches in the upper edge of said swivel ring, and an arm secured on said tone arm and extending downwardly to anchor the lower end of said tone arm.

In testimony whereof I affix my signature.
WILLIAM T. CARNES.
